UNITED STATES PATENT OFFICE.

SAMUEL HOLMES AND WILLIAM M. BOWRON, OF PHILADELPHIA, PA.

IMPROVEMENT IN IRON SHIP-BUILDING.

Specification forming part of Letters Patent No. 139,789, dated June 10, 1873; application filed
March 27, 1873.

To all whom it may concern:

Be it known that we, SAMUEL HOLMES and WILLIAM MOSS BOWRON, both formerly of Stockton-on-Tees, county of Durham, England, but now residing in Philadelphia, Pennsylvania, have invented an Improvement in the Construction of Iron Vessels, of which the following is a specification:

The object of our invention is to construct iron vessels in a more permanent and substantial manner than heretofore, without additional weight of metal, and this object we attain by discarding the usual angle-iron or T-iron transverse ribs, and employing the longitudinally-flanged plates shown in the accompanying drawing, which represents a partial mid-ship section of an iron vessel built according to our invention.

The entire shell of the vessel is composed of longitudinal plates A, having flanges formed on two edges, as shown. The flanges of the adjoining plates may be riveted together, but we prefer to weld them by means of apparatus for which we have made a separate application for a Patent. The united flanges of the plates form a series of ribs arranged in a longitudinal direction, which

enables them to present a much more efficient resistance to the strains to which the vessel is subjected than the usual transverse ribs of angle or T-iron. Where the vessel has to be strengthened toward the keel, longitudinal ribs b b may be confined between and secured to the flanges of the plates, and, whenever the vessel demands, a substantial longitudinal girder, B. The upper and lower plates of this girder may be secured between or at either side of the flanges of the plates A, as shown in the drawing, in which the method of connecting the deck-beams to the plates is too clearly illustrated to need description.

We claim as our invention—

As a new structure, a vessel having longitudinal ribs composed of the united flanges of plates which form the skin of the vessel.

In testimony whereof, we have signed our names to this specification in the presence of two subscribing witnesses.

SAMUEL HOLMES.
WILLIAM MOSS BOWRON.
